UNITED STATES PATENT OFFICE.

ABRAHAM L. MAXIM, OF OMAHA, NEBRASKA.

MITER-MACHINE.

SPECIFICATION forming part of Letters Patent No. 478,449, dated July 5, 1892.

Application filed July 13, 1891. Serial No. 399,309. (No model.)

To all whom it may concern:

Be it known that I, ABRAHAM L. MAXIM, a citizen of the United States, residing at Omaha, in the county of Douglas and State of Nebraska, have invented a new and useful Miter-Machine, of which the following is a specification.

This invention relates to a new and improved miter-machine, and has for its object 10 the production of a device of this nature capable of quick and easy adjustment to any angle and which shall be simple in construction, inexpensive, compact and durable.

The invention comprises the detail construction, combination, and arrangement of parts, substantially as hereinafter fully set forth, and particularly pointed out in the claims.

In the accompanying drawings, Figure 1 is 20 a view in perspective of my improved miter-machine. Fig. 2 is a top plan view thereof. Fig. 3 is a bottom view. Fig. 4 is a front elevation, partly in section. Fig. 5 is an end view. Fig. 6 is a sectional view showing one 25 of the guide-posts connected to its bed or base. Fig. 7 is a transverse sectional view on the line $x-x$, Fig. 2. Fig. 8 is an enlarged view of the scales of graduations. Fig. 9 shows one of the saw-guides in different positions.

Referring to the drawings, A designates the 30 base or platform provided at one side with an elongated portion a. The front of this base or platform is curved to form a semicircle, and upon its upper surface are two scales of graduation a a', the former scale serving as a 35 guide for the adjustment on the outer scale. The numbers of the inner scale extend from the saw-line ninety degrees to right angle, and the numbers of the outer scale back ninety 40 degrees to the forty-five-degrees line. In this base A, adjacent to the inner scale of graduation, is a circular slot or opening a², while adjacent to the center of the cord of said base is a second but shorter-curved slot or opening a³.

B B' designate two supporting-posts provided with vertical slots b, extending from their upper down to near their lower ends. These posts have lower reduced ends b', which 50 are threaded and screwed into corresponding holes or openings, one at about the center of

the cord or straight side of the base and the other at the outer end of the elongated portion a of said base. In opposite grooves in these posts are saw holders or guides C, which 55 are provided with longitudinal slots C', terminating at their ends in slightly-enlarged openings, said upper openings serving to form shoulders C² for the upper thickened portion of the saw-blade X to rest thereon. Through 60 openings in overhanging portions d of these saw holders or guides are adjustable screws D. These screws, by reason of contact with the upper ends of posts B B', serve to limit the downward movement of the saw holders 65 or guides and prevent the saw from descending too far and thus sawing the base, and by being adjustable as the saw wears it may be farther lowered. A pin or stud d', projecting from each post, is in the path of a lug d² of 70 each saw holder or guide, and thus limits the upward movement of the latter. These lugs d² serve as stops to prevent the accidental removal of the saw holder or guide when being raised in the posts. 75

E is a slide designed to move over the base A and describe an arc of a circle, its inner end being coincident with post B. This slide consists of a vertical plate e, having an inner widened right-angular portion e' bearing on 80 said base and an outer elongated portion e² projecting beyond said base. At its extreme outer end it is provided with a right-angular lip or tongue e³, designed to support the block or piece of wood or other article to be sawed. 85 From the under side of the widened portion e' project two lugs or flanges e⁴ e⁵, which are respectively projected through the slots or openings a² a³ of base A, said lug or flange e⁵ being provided with a lower reduced end e⁶. 90

F is a clamp, which consists of an arm f, having a rear circular end f', through an opening in which the lower end of post B is projected, a boss f² on said end fitting snug against said base around said post. The reduced end e⁶ of lug or flange e⁵ is extended through a hole in arm f, and the latter fits snug in a corresponding-shaped groove in lug or flange e⁴, its outer end being in contact with a rib f³ on the under side of base A adjacent the curved edge thereof. Through coincident holes in arm f, lug e⁴, base A, and 100

widened portion of slide E is passed a threaded rod or screw f^4 , the head of which is countersunk in the under side of said arm f. On the upper projecting end of rod or screw f^4 is a 5 binding nut or arm G, from which projects a vertical flange g, by which the nut or arm can be readily operated, according as it is desired to tighten or loosen the clamp. A plate-spring g' is secured at g^2 to the under side of arm f of said clamp, and its outer free end fits in the slot in the head of screw f^4 , holding the same, as against turning. Hence to loosen or bind the clamp it is only necessary to turn this binding nut or arm.

15 From the under side of the elongated portion of slide E project two lugs h, through coincident holes in which is passed a spring-pressed bolt h', having an outer headed end h². The inner end of this spring-bolt is 20 signed to enter any one of a series of holes h³ in the curved side of base A.

In practice by placing a bevel to the saw X and slide E the desired degree or inclination will be indicated on the inner scale of 25 graduation on base A, and then by adjusting said slide to the corresponding graduation on the outer scale the miter-cut for the degree first indicated will be obtained.

The advantages of my improved miter-machine are apparent to those skilled in the art. 30 It will be especially observed that the same is very simple in construction, is capable of ready and easy operation, is accurate in its measurements, and is inexpensive.

35 I claim as my invention—

1. The herein-described improved miter-machine comprising the base, having the inner and outer saw-supporting posts at one side thereof, the slide movable thereover in 40 circular relation to said inner post, the clamp beneath said base provided with an inner circular end surrounding said inner post and having engagement with said slide, and means

for binding said clamp to said slide, substantially as set forth. 45

2. The herein-described improved miter-machine comprising the base, having the saw-supporting posts at one side thereof and provided with curved slots, the slide having lugs projected through said slots, the clamp pivoted on the under side of said base and engaging said lugs, the threaded rod or screw connecting said clamp with said slide, and the binding nut or arm on said rod or screw, substantially as set forth. 55

3. The herein-described improved miter-machine comprising the base having the saw-supporting posts at one side thereof and provided with curved slots, the slide having lugs extending through said slots, the clamp having a circular portion encircling one of said posts, the rod or screw connecting said clamp with said slide and having a slot in its lower head, the plate-spring secured to said clamp at one end and having its free end in said 60 slot, and the nut or arm in the upper end of said rod or screw having a vertical flange or projection, substantially as set forth.

4. The herein-described improved miter-machine comprising the circular base having an arm or elongated portion provided with 70 threaded openings, the slotted posts having reduced threaded ends fitting said openings and provided with projecting pins or studs, the saw-holders or guides movable in grooves 75 in said slotted posts and having upper overhanging portions, the adjustable screws working in holes in said overhanging portions, and the lugs projecting from said saw-holders or guides and designed to limit the upward 80 movement of the latter by contact with said pins or studs, substantially as set forth.

ABRAHAM L. MAXIM.
